INVENTOR:

John W. Lockerbie
by Chas. T. Evans Atty

UNITED STATES PATENT OFFICE.

JOHN W. LOCKERBIE, OF MARBLEHEAD, MASSACHUSETTS.

IRONING MACHINE.

Application filed April 14, 1923. Serial No. 631,960.

To all whom it may concern:

Be it known that I, JOHN W. LOCKERBIE, a citizen of the United States, residing at Marblehead, in the county of Essex and 5 State of Massachusetts, have invented new and useful Improvements in Ironing Machines, of which the following is a specification.

This invention is an improvement in 10 household mangles or ironing machines.

One of the objects of the invention is to provide means for supporting such a machine and its driving mechanism in a horizontal position when in use, and in a vertical 15 position when not in use, so as to economize space in the kitchens of dwelling houses, particularly apartments. A further object is to provide means for so supporting the ironing machine and its driving mechanism that they may be readily and conveniently moved to either position at will. A further object is to provide means by which the ironing machine and its driving mechanism may be protected from dust and vapor 20 when not in use.

In the accompanying drawing illustrating 30 my invention Fig. 1 is a perspective view of the cabinet when it is open and ready for the use of the machine.

Fig. 2 is a side elevation with the machine in a vertical position within the cabinet.

Fig. 3 is a plan view of the machine in use and of a horizontal section of the cabinet 35 through the line X—X in Fig. 2.

Similar numerals refer to corresponding parts on all the figures of the drawing.

Referring to the drawing, 4 is an upright cabinet or support approximately five 40 feet in height, mounted on feet 5; 6 is a table supporting an ironing machine or mangle 7, suitable for household use. The table 6 is pivoted at 8 to swing the mangle into and out of the cabinet 4. The cabinet 4 is approximately 15 to 16 inches square. The 45 length of the table 6 is slightly less than the inside height of the cabinet 4, so as to be completely enclosed within it when the mangle 7 is not in use. 26 is a rod secured to the under side of the table 6, the 50 ends of which are journalled in brackets 10 in the sides of the cabinet. 9 is a heavy steel helical spring surrounding the rod 8 and having one end 11 secured to the table 6, and the other end 12 secured to the inner 55 wall of the cabinet counterbalancing the

weight of the table 6 and the machine 7. It is to be understood that the term "counterbalance" and "counterbalancing", as used in the specification and claims, are intended to mean and are construed to refer to and to include the force tending to partially overcome the weight of the ironing machine as well as wholly to overcome it. 13, 13 are 60 legs supporting the table 6 when in use. 14 forms the front wall of the cabinet 4, and is secured to and also forms a part of the table 6. 15, 15 are recesses in the wall 14 to receive the legs 13, 13 and present them flush with the wall 14 when the cabinet is closed. 70 16 is a torsional spring secured at one end to the edge of the table 6 and at the other end to the bottom of the cabinet at 17. When the machine is in use and the table 6 is in a horizontal position or in a vertical 75 position, the spring 16 is at its maximum tension, and when the table is at an angle of about 45 degrees the tension of the spring 16 is neutral. The function of the spring 16 is to aid the operator in opening the 80 cabinet, and also to cooperate with the spring 9 in assisting the operator in closing it. 18 is an electric motor adapted to take the current from house fixtures by any of the well known connections, such as a plug 85 and socket 19 in the wall of the cabinet at any suitable and convenient place. 20 is the driving belt, and 21 the driving pulley on the shaft 22 on which is provided a worm driving the main roll 23 of the mangle 7 through a worm gear 27 and the gears 24 and 25.

I do not limit my invention to the particular style of mangle shown nor to any particular type of motor or mechanism for operating it.

The advantages to be derived from this construction are of great value in utilizing space, for the constant presence of a machine approximately four feet in length in 100 many kitchens is prohibitive, and in all is a great inconvenience.

It is obvious that a cabinet made of wood, metal or any other suitable material would be embraced within my invention, and if desired it may be constructed in and form a part of the wall of a kitchen or laundry. Such a receptacle for the machine, built into the wall of a house and possessing the other features of my device, would likewise be 110 within the scope of my invention.

It is apparent that the table 6 as a sepa-

rate and distinct part may be dispensed with and that the wall 14 may be made intact and pivoted at 8 as shown, to swing vertically instead of composed of two sections one of which is fixed and the other movable. In such case the wall must, of course, be pivoted so as completely to close the cabinet when it is raised to a vertical position with the ironing machine and its driving mechanism enclosed within the cabinet.

What I claim and desire to secure by Letters Patent is:

1. A device of the character described comprising a support, a table pivotally connected to said support on a horizontal axis, whereby it is movable from vertical to horizontal positions and vice versa, an ironing machine carried by said table, and a driving motor for the ironing machine, said driving motor being so positioned relatively to said ironing machine as to counterbalance the latter during pivotal movement of the table.

2. In a device of the character described the combination of an ironing machine and its driving mechanism, a support adapted to sustain the same when the ironing machine is in an upright position, a table for the ironing machine and its driving mechanism, said table being pivoted to said support on a horizontal axis and extending at one end a substantial distance beyond said axis, said extension having secured thereto means contributing to counterbalance the ironing machine.

3. In an upright receptacle for an ironing machine, a tilting table, pivoted in the wall of said receptacle, and extending into the receptacle a distance approximately equal to the horizontal depth of the receptacle, said table having an ironing machine secured to that portion of the table extending beyond the receptacle, and a driving mechanism secured to that portion of the table extending within the receptacle.

4. An upright cabinet comprising one movable wall adapted to close the cabinet, said wall being pivoted to said cabinet on a horizontal axis, at a distance from its lower end substantially equal to the horizontal depth of the cabinet, combined with an ironing machine, and driving mechanism for said ironing machine, said driving mechanism being so positioned relatively to the ironing machine as to counterbalance the latter during pivotal movement of said wall.

5. An upright cabinet comprising an opening in one wall combined with a table pivoted to said cabinet on a horizontal axis and extending within the cabinet, and an ironing machine and driving mechanism

therefor secured to said table, said axis being located adjacent to the space between the ironing machine and said driving mechanism.

6. An upright cabinet comprising a wall 65 divided on a horizontal axis into two sections, the lower section being stationary, a table being secured to the upper section and extending into the cabinet, said upper section being hinged to the lower section so as 70 to swing on said horizontal axis to open and close the cabinet, combined with an ironing machine and driving mechanism therefor secured to the said table, the ironing machine being located substantially above 75 said axis and the driving mechanism located substantially below said axis when the cabinet is closed.

7. An upright cabinet comprising a wall divided on a horizontal axis into two sections, the lower section being stationary, a table secured to the upper section and extending into the cabinet a distance approximately equal to the horizontal depth of the cabinet, said upper section being hinged to 80 the lower section so as to swing on said horizontal axis to open and close the cabinet, combined with an ironing machine secured to that portion of the table extending outside of the cabinet and a driving mechanism for said ironing machine secured to 85 that portion of the table extending within the cabinet. 90

8. A device of the character described comprising a support, a table pivotally connected to said support on a horizontal axis, an ironing machine supported upon said table, a motor mounted upon said table and adapted to operate said ironing machine, said table extending at one end beyond said 95 axis combined with a torsional spring connected to said extension and to the base of the support. 100

9. A cabinet comprising a wall pivoted on a horizontal axis and adapted thereby to 105 open and completely close the cabinet, combined with an ironing machine and driving mechanism therefor secured to the inside of said wall, said ironing machine being located substantially above and said driving mechanism substantially below said axis when the cabinet is closed.

In testimony whereof I have hereunto set my hand in presence of two subscribing witnesses, this ninth day of April, 1923.

JOHN W. LOCKERBIE.
